UNITED STATES PATENT OFFICE.

WILHELM WOLF, OF REISHOLZ, NEAR DÜSSELDORF, GERMANY.

VALVE FOR COMPRESSORS AND THE LIKE.

No. 851,722.

Specification of Letters Patent.

Patented April 30, 1907.

Application filed December 4, 1906. Serial No. 346,310.

To all whom it may concern:

Be it known that I, WILHELM WOLF, a subject of the King of Prussia, residing at Reisholz, near Düsseldorf, Kingdom of Prussia, Germany, have invented new and useful Improvements in Valves for Compressors and the Like, of which the following is a specification.

My present invention relates to improvements in valves specially suitable for compressors and belonging to that class in which a tubular spindle is enlarged like the mouth of a trumpet toward the valve seat.

The invention consists essentially in constructing the valve of thin sheet metal and providing the same with a concaved bottom which also consists of thin sheet metal and is rigidly connected thereto for example by soldering or brazing so that by bending the trumpet like part the bottom is also bent and vice versa. By this arrangement the advantage is obtained that the valve can be constructed of extremely thin sheet metal even for large valve openings. The sheet metal can be chosen much thinner than in the case of plane or arched plate valves, because the trumpet like part of the spindle forms a triangular stiffening for the arched bottom when the valve is seen in vertical section. Owing to the possibility of using very thin metal the resilient properties of the valve, which as well known are very favorable for the efficiency of the machine, are assured and are better emphasized in operation than before.

In the accompanying drawing illustrating my invention Figure 1 shows a suction valve and Fig. 2 a pressure valve in vertical section. Figs. 3 and 4 show modified constructions of suction and pressure valves and Fig. 5 shows the unrolled spring used according to Fig. 3.

The tubes *a* and *i* of Figs. 1 and 2 are made of steel or of good gun metal and are expanded at the bottom by pressure or other means so that they extend in an easy curve to the seats *f* and *n*. In the suction valve shown in Fig. 1 this curved extension forms the facing *e* of the valve, while in the pressure valve shown in Fig. 2 the edge is bent up at *m* to produce the facing. The hollow space at the bottom of the valve is closed by a thin sheet metal plate *d* or *l* which is concaved into the trumpet like part of the spindle in order to pro-

vide room for the curved surface of the piston *h*. Said bottom plate *d* or *l* can be attached by inserting its edge in a groove *c* or *k* formed in shaping the trumpet like end. The concaved plate is arranged to fit tightly and is brazed or soldered, so that it is securely fastened to the border.

It is of advantage to taper off the thickness of the sheet metal toward the edge of the valve so that this part *e* will be more resilient of itself. By this means it is assured that the valve is closed without a shock. The entire valve consists therefore, as it were, of two resilient parts, one of which is formed by the triangularly stiffened trumpet part and concaved bottom and the other by the edge *e*.

In what manner the valve can be loaded by springs *z*, *z'* as well as guided and limited in movement by ribs *g* and *o* will be apparent from Figs. 1 and 2. In Fig. 1 the spring *z* bears against a flange *b*, whereas the bent up border *m* serves the same purpose in Fig. 2.

In the construction shown in Fig. 3 the concaved bottom *p* of the suction valve is provided with an annular groove *q*, against which the trumpet like expanded end of the valve *a* bears, these parts being connected by soldering or brazing. This valve (Fig. 3) is shown loaded by a flat spring *r* which has a crown shape and is provided with downwardly extending tongues *t*, said spring being supported by lugs *s*, on the guide *g'*.

The pressure valve shown in Fig. 4 has a facing *v* formed by bending up the edge of the concaved bottom *u*. A still greater resiliency of the trumpet like expanded part is produced by providing openings *w* therein. Such openings can also be provided in the constructions shown in the other figures. Further the springs can be omitted and the other means adopted to load the valves.

I claim

1. A valve comprising a sheet-metal tubular valve-stem having a flared lower end, a concave sheet-metal valve-plate secured to and covering said flared end of the stem, and means to seat the valve.

2. A valve comprising a sheet-metal tubular valve stem having a slotted, flared lower end to increase its resiliency, a concave sheet-metal valve-plate secured to and covering said flared end, and means to seat the valve.

3. A valve comprising a sheet-metal tubular valve-stem having a slotted, flared lower end, a concave sheet-metal valve-plate secured to and covering said flared end and 5 having an annular portion turned above the flared end of the stem.

4. A valve comprising a sheet-metal tubular valve stem having a flared lower end, a concave sheet-metal valve plate secured to 10 and covering said flared end and having an annular portion turned above the flared end of the stem forming an abutment, a guide

surrounding the valve stem having a flange formed thereon, and a spring surrounding the guide bearing against the abutment and 15 flange.

In testimony whereof I affix my signature to this specification, in the presence of two witnesses:

WILHELM WOLF.
